UNITED STATES PATENT OFFICE.

JOSEPH J. RISCHARD, OF PASADENA, CALIFORNIA.

VALVE-GRINDING TOOL.

1,271,488.

Specification of Letters Patent. Patented July 2, 1918.

Application filed January 9, 1918. Serial No. 211,045.

To all whom it may concern:

Be it known that I, JOSEPH J. RISCHARD, a citizen of the United States, residing at Pasadena, in the county of Los Angeles and 5 State of California, have invented new and useful Improvements in Valve-Grinding Tools, of which the following is a specification.

My object is to make a tool for use in re-10 grinding the valves of a gas engine, the tool being constructed to grip the valve and there being a joint in the handle so that reasonable vibration of the handle will not loosen the grip.

15 Figure 1 is a view illustrating the use of a valve grinding tool embodying the principles of my invention, the head of the engine being shown in section and broken away and the tool being shown in elevation and 20 connected to the valve.

Fig. 2 is an enlarged detail view analogous to Fig. 1.

Fig. 3 is an enlarged sectional detail on the line 3—3 of Fig. 2.

25 Fig. 4 is a sectional detail on the line 4—4 of Fig. 2.

Fig. 5 is a view analogous to Fig. 2 and showing a modified construction of the tool.

30 Fig. 6 is a fragmentary side elevation as seen looking in the direction indicated by the arrow 6 in Fig. 5.

Fig. 7 is an enlarged cross-sectional detail on the line 7—7 of Fig. 5.

Fig. 8 is an enlarged edge view looking 35 in the direction indicated by the arrow 8 in Fig. 6.

The handle 1 is rigidly secured to a square stem 2 having parallel transverse openings 3 and 4 near its lower end. The gripping 40 jaws 5 and 6 are made from sections of the same square material as the stem 2 and said jaws have openings 7 and 8 in their upper ends through which a cotter pin 9 is inserted, said cotter pin also passing through 45 the opening 3 to pivotally connect the jaws to the stem, the openings 7 and 8 being large enough to allow the lower ends of the jaws to swing to and from the lower end of the stem. A wing headed screw 10 is screw- 50 seated through the lower end of the jaw 6 and passes loosely through the opening 4 into the socket opening 11 formed from the inner face of the jaw 5, so that when the screw 10 is operated to screw inwardly the lower 55 ends of the jaws 5 and 6 are pressed apart

and so that when the operation of the screw is reversed the jaws may come toward each other and against the sides of the stem 2. The lower ends of the jaws 5 and 6 extend below the lower end of the stem 2 and said 60 lower ends are turned to produce the necks 12 and 13 and the gripping teeth 14 and 15 upon the extreme lower ends of the necks.

In the use of this tool the plug is removed from the opening 16 in the head 17 of the 65 engine and the tool is inserted downwardly through the opening 16 to engage the valve 18. The necks 12 and 13 extend downwardly into the spanner recesses or key sockets 19 and 20 formed from the upper face 70 of the valve 18, so that the lower faces of the teeth 14 and 15 engage the bottoms of the recesses. Then the screw 10 is operated to throw the jaws 5 and 6 apart, thereby forcing the teeth 14 and 15 to cut into the 75 metal at the sides of the recesses. This will cause the tool to grip the valve and as the handle 1 is rotated by rubbing the two hands of the operator in opposite directions against the handle, the valve 18 will be rotated to 80 grind itself into its seat. The lower end of the stem 2 may vibrate between the jaws 5 and 6, thus allowing for the vibration of the handle 1 between the hands of the operator and reducing the liability of loosening the 85 grip of the tool upon the valve. When the grinding operation is complete the screw 10 is loosened and the tool withdrawn.

In the modification shown in Figs. 5—8 the valve 21 is manufactured with a transverse 90 slot 22 extending from its upper face, and the tool is constructed to grip in this slot instead of gripping in spanner recesses, as in Fig. 2. The handle 23 is rigidly secured to the upper end of the stem 24 and a bifurcated bearing 25 is formed upon the lower 95 end of the stem 24. The jaws 26 and 27 are flat and their heads 28 and 29 fit close together and fit in the bifurcation 30 of the bearing 25, and a pivot bolt 31 is inserted 100 through the bearing and through the heads to form a pivotal connection between the stem 24 and the jaws 26 and 27. The jaws 26 and 27 normally fit flat together, and a wing headed set-screw 32 is screw-seated 105 through the jaw 27 against the jaw 26, so that it may be screwed inwardly to spread the lower ends of the jaws apart. The jaws 26 and 27 are notched from their end faces 110 to form the necks 33, 34, 35 and 36, the necks

33 and 35 being staggered to be opposite the notches which form the necks 34 and 36, and said necks 33 and 35 are off-set inwardly half the thickness of the metal, and the necks 5 34 and 36 are off-set inwardly half the thickness of the metal, so that when the screw 32 is backed out and the jaws 26 and 27 come flat together the necks 33, 34, 35 and 36 are in a line to pass into the slot 22 and down 10 to the bottom of the slot. Sharp teeth 37 project outwardly from the lower ends of the necks 33 and 35, and corresponding sharp teeth 38 project outwardly from the lower ends of the necks 34 and 36, so that when the 15 screw 32 is operated to press the jaws 26 and 27 apart the teeth 37 and 38 will cut into the metal at the sides of the slot 22 and grip the tool to the valve. The pivot joint formed by the bolt 31 allows for the vibration of the 20 handle 23 in the operation, and when the

grinding operation has been completed the screw 32 is loosened and the tool withdrawn.

While I have shown the preferred construction of my valve grinding tool, it will be understood by those skilled in the art 25 that various changes in the construction, combination and arrangement of parts may be made, without departing from the spirit of my invention as claimed.

I claim:

A valve grinding tool comprising a handle, a stem rigidly fixed to the handle, jaws flexibly connected to the stem and having teeth adapted to grip a valve head in its key sockets, and a set-screw carried by one jaw and 35 engaging the other to force the jaws apart and cause the teeth to grip.

In testimony whereof I have signed my name to this specification.

JOSEPH J. RISCHARD.
